DESIGN FOR A FRONT FOR TRAVELING BAKE OVENS

Fred C. Haller, Pittsburgh, Pa., assignor to Haller Oven Company, Pittsburgh, Pa., a corporation of Pennsylvania

Application April 26, 1933, Serial No. 47,901

Term of patent 14 years

To all whom it may concern:

Be it known that I, FRED C. HALLER, a citizen of the United States, residing at Pittsburgh, in the county of Allegheny and State of Pennsylvania, have invented a new, original, and ornamental Design for a Front for Traveling Bake Ovens, of which the following is a specification, reference being had to the accompanying drawing, forming a part hereof.

The figure shows a front perspective view of a front for traveling bake ovens embodying my design.

I claim:

The ornamental design for a front for traveling bake ovens, as shown.

In testimony whereof, I have hereunto subscribed my name this 21st day of April, 1933.

FRED C. HALLER.
